SAW TRIMMER VISE

William Hertler, Pittsburgh, Pa.

Application March 14, 1938, Serial No. 195,809

2 Claims. (Cl. 29—69)

This invention relates to new and useful improvements in a saw-trimmer vise, and it is among the objects thereof to provide a vise which shall be adapted to be detachably mounted to a saw table for trimming slugs, such as spacers for printing set ups and the like in printing plants.

A saw-trimmer vise is essentially constructed to embody a single jaw movably mounted to be extensible over a wide range in cooperation with a stationary abutment of the table on which it is mounted to engage the different size pieces to be trimmed by the saw, and in addition the movable jaw, when set to its adjusted position for engagement with the piece, must be capable of intimately locking or engaging that piece. Various means have been heretofore proposed for combining with the means for quickly extending the jaw, a means for securely locking it in clamping position.

20 In accordance with the present invention, such a device of simple and efficient construction is provided, the character and structural features of which will become more apparent in connection with a description of the accompanying drawing constituting a part hereof.

In the drawing, in which like reference characters designate like parts,

Fig. 1 is a side elevational view of a saw-trimmer vise embodying the principles of this invention with the locking lever in the extended or open position;

Fig. 2 a sectional elevational view thereof taken along the line 2—2, Fig. 1;

Fig. 3 a side elevational view of a detail of the structure shown in Fig. 1 with the locking lever in the down or clamping position;

Fig. 4 a front elevation of a lever actuated eccentric embodied in the locking mechanism; and

Fig. 5 a side elevation of Fig. 4.

40 With reference to the several figures of the drawing, numeral 1 designates a table adapted for movement in the direction of a saw designated by the numeral 2; 3 designates a fixed abutment on the table against which a piece 4 to be trimmed is clamped by a serrated or otherwise roughened surface 5 of a clamping bar 6. The bar 6 is cut out at 7 to reduce the face 5 to substantially the size of piece 4 to be engaged and clamped. It is desirable that the bar 6 be movable over a substantial distance from the abutment 3 on the table for the distance the piece to be clamped will extend from the abutment, and as heretofore stated, provision is made to facilitate the extension of the clamping bar and the clamping or gripping movement or function

of the slide bar to quickly and securely clamp the piece to be acted upon by the saw.

Mechanism for this purpose consists of the following means. A base 8 having end blocks 9 and 10 is adapted for fastening to the table 1, by a hand screw 11, which interacts with a threaded portion of the table, and a pin 11a having a peripheral groove 12, which interacts with a pin 13 secured in the table, so that by twisting the base 8, pin 11a will fall into the opening provided therefor in the table, and when swinging the vise to the position where the hand screw 11 is in alignment with the threaded opening in the table, the groove 12 will interlock with the pin 13 to prevent displacement of the base. Thus the vise is rigidly secured to the table 1.

A guide bar 14 is mounted between end blocks 9 and 10, the bar 14 being of a rectangular or square shape, as shown in Fig. 2, excepting at its respective ends where it is rounded as at 15 and 16 to fit into cylindrical openings in the blocks 9 and 10, the end of the guide bar 14 that is disposed in the end block 9 abutting against a coil spring 17 which is held in place by a screw 18 for the purpose to be hereinafter explained.

The clamping bar 6 is provided with a dovetail slide bar 20 which is fastened to the clamping bar 6 in any suitable manner as by screws 21. The dovetail member 20 interacts with the dovetail grooves or guideways 22 provided in end blocks 9 and 10 and the clamping bar 6 is freely slideable in the dovetail guideways 22 of the base.

The clamping bar 6 is locked against sliding movement by means of the following mechanism. A clamping block 23 having a V-shaped slot for resting on the upper triangular faces of the guide bar 14 is freely slideable on the guide bar 14 unless clamped to the latter, which clamping is effected by a movable block or gib 24, the gib being provided with a bore for receiving the eccentric pin or shaft 25, Fig. 4, which is actuated by a lever 26. The end 27 of shaft 25 fits into the clamping block 23 as shown in dotted lines in Fig. 2, and the end of shaft 25 adjacent the lever 26 is provided with a bushing 28 which fills the opening made in the block 23 of such size as to permit the eccentric portion 25 being inserted therein. When lever 26 is actuated, the gib block 24 will be forced in intimate clamping engagement with the guide bar 14 by the action of the eccentric 25, and by throwing lever 26 to the opposite direction, the gib will be released and the block 23 will be freely movable thereon.

As shown in Figs. 1 and 3, lever 26 is actuated

by a lever 30 having a handle 31, levers 26 and 30 being connected by a link 32. Lever 30 is pivotally mounted at 33 on a block 34 which is securely attached to the clamping bar 6 to be movable therewith, and block 34 is movable relative to block 23 within the limits of the abutments constituted by one side of block 23 and an abutting plate 35 attached to the slide bar 6 by a screw 36. A rod 37 is secured to block 23 by screw 38 and extends through a perforation or opening in the abutting plate 35. Coil spring 39 is disposed around the rod 37 with one end of the spring abutting the plate 35 and the other end abutting an adjustable screw sleeve 40 which interacts with a threaded portion of the rod 37. A stop pin 41 is provided on the block 34 for lever 30.

The operation of the above described mechanism is briefly as follows: The trimmer vise is fastened as shown in Fig. 1 with the screw 11 and pin 11a inserted in the table to securely fasten the base 8 thereto which, when fastened, brings the clamping slide 6 in register with the edge of the abutment 3. With the handle 31 in the raised position, as shown in Fig. 1, the eccentric 25 is in a position where the gib block 24 is out of contact with the guide rod 14. In this position, block 23 is free to slide on the guide 14, which permits quick adjustment of the clamping bar 6 to any position necessary to engage the piece 4 by simply drawing the bar 6, which is accomplished by pulling handle 31, in the direction of the piece 4, to bring the clamping bar 6 either adjacent to or in contact with the piece 4. The latter will be clamped by the action of depressing handle 31 to the horizontal position as shown in Fig. 3. By this movement of handle 31, the clamping bar 6 moves forward in the direction of the piece 4, and by the leverage of lever 30 through the link 32 against lever 26, the latter will be depressed, causing the eccentric 25 to rotate, resulting in the gib block 24 pressing against the guide bar 14 and locking bar 23 in position. Downward movement of the handle 31 compresses spring 39, as shown in Fig. 3, and by raising handle 31 upward the locking mechanism will be released by a spring action.

When the clamping face 5 of the bar 6 is brought to abutting engagement with the piece to be clamped, the clamping action, by depressing handle 31, first locks the block 23 to the guide rod 14, and by further depressing handle 31, the entire guide bar 14 is moved rearward against the tension of the coil spring 17 so that the piece 4 is held against the abutment 3 by the back pressure of the coil spring 17. When handle 31 is raised, the power of the compressed spring 17 also acts to snap the handle 31 to the uppermost position and retract the clamping bar 6 to release the piece 4. The eccentric, however, remains locked so that the clamping bar 6 will always return to the position to which it was originally adjusted for the particular size pieces to be acted upon, and if it is desired to change the position of the clamping slide bar 6 by moving the block 23 on the guide bar 14, it is necessary to raise the handle 31 until lever 30 abuts the pin 41, which movement releases the eccentric and con-

sequently the clamping block 23, which is then free to slide on the bar 14.

By means of the hereinbefore described mechanism, adjustment of the clamping bar to different size pieces can be made by manipulation of the same handle or lever that is employed for clamping the piece, whereby the size is quickly adjustable to the different size pieces to be sawed or trimmed. Also the eccentric locking mechanism, and the spring biasing of the guide rod provide a reliable and positive locking means for the pieces. The device is of compact and durable construction and as will be appreciated from the nature of the construction of the operating mechanism, there is very little strain on the working parts, so that they will last indefinitely. As the eccentric shaft has a precision fit with the movable gib block, it is not subject to excessive wear, and the gib block being coextensive with the block 23 has a side-contacting surface for clampingly engaging the guide rod 14 so that it likewise is not subjected to any wear and will not mar the guide rod 14, which would hamper the free sliding of the mechanism.

Although one embodiment of the invention has been herein illustrated and described, it will be evident to those skilled in the art that modifications may be made in the details of construction without departing from the principles herein set forth.

I claim:

1. A vise comprising a base, a stationary abutment in spaced relation to said base, a clamping bar slidably mounted on said base in alignment with said stationary abutment, means for extending said bar and for locking it comprising a guide rod on said base, a clamping block slidably mounted on said rod, a gib in said block adapted to engage the rod, an eccentric for actuating said gib to engage and disengage the guide rod, a lever for actuating said eccentric, a lever carried by the clamping bar for actuating said first named lever, said levers being connected by a link, spring means biasing said clamping bar against the clamping block, and spring means biasing the guide rod against the base whereby, upon downward movement of the clamping bar lever, the piece to be acted upon is yieldingly engaged between the clamping bar and the stationary abutment.

2. A vise comprising a stationary base, a clamping bar movably mounted thereon, a guide rod mounted for limited axial movement in said base, a spring biasing said guide rod, a clamping block mounted on said guide rod, a gib block in said clamping block, an eccentric for actuating the gib block to engage and disengage the guide rod, a lever for actuating the eccentric, and a lever mounted on said clamping bar and connected to said first named lever, and spring means biasing said lever to the upper position, said lever being operative to release the gib block when it is desired to slide the clamping block on the guide rod to extend the clamping bar and being operative to move the clamping bar in clamping engagement with the piece to be acted upon without affecting the gib block actuating lever.

WILLIAM HERTLER.
